(57) **CLAIM**

The ornamental design for a neural net adaptor, as shown and described.

DESCRIPTION

FIG. 1 is a top front perspective view of a neural net adaptor in accordance with the claimed design;

FIG. 2 is a bottom rear perspective view thereof;

FIG. 3 is a top plan view thereof;

FIG. 4 is a bottom plan view thereof;

FIG. 5 is a front elevation view thereof;

FIG. 6 is a left side elevation view of the design of FIG. 1;

FIG. 7 is a right side elevation view thereof; and,

FIG. 8 is a rear elevation view of the design of FIG. 1.
